(57) **CLAIM**

The ornamental design for a path light, as shown and described.

DESCRIPTION

FIG. 1 is a front right top perspective view of a path light showing our new design;

FIG. 2 is a front left bottom perspective view thereof;

FIG. 3 is a front elevation view thereof;

FIG. 4 is a rear view thereof;

FIG. 5 is a top plan view thereof;

FIG. 6 is a bottom view thereof;

FIG. 7 is a left side view thereof; and,

FIG. 8 is a right side view thereof.

The broken lines shown in the drawings illustrate portions of the path light that form no part of the claimed design.
